UNITED STATES PATENT OFFICE.

PATSY BELOTT, OF CLARKSBURG, WEST VIRGINIA.

DESIGN FOR A CLOCK-CASE.

55,972.

Specification for Design.

Patented Aug. 10, 1920.

Application filed November 13, 1919. Serial No. 337,864. Term of patent 14 years.

To all whom it may concern:

Be it known that I, PATSY BELOTT, a citizen of the United States, residing at Clarksburg, in the county of Harrison and State of West Virginia, have invented a new, original, and ornamental Design for a Clock-Case, of which the following is a specification, reference being had to the accompanying drawings, forming a part thereof.

Figure 1 represents a perspective view of the clock case, showing the new design mounted upon a base, and having an ordinary

clock inserted in the center of said case.

Fig. 2 represents a vertical section of the clock case and base, the clock being removed.

Fig. 3 represents a side elevation of said case and base, constituting my new design.

What I claim is:

The ornamental design for a clock case, as shown and described.

PATSY BELOTT.
